GRINDING MACHINE

Raymond H. Cramer, Bloomfield, N. J., assignor to General Motors Corporation, Detroit, Mich., a corporation of Delaware

Original application July 30, 1940, Serial No. 348,398, now Patent No. 2,311,213, dated February 16, 1943. Divided and this application May 20, 1942, Serial No. 443,756

16 Claims. (Cl. 51—165)

This invention relates to grinding machines and comprises all of the features and aspects of novelty herein disclosed. An object of the invention is to provide an improved sizing mechanism for controlling the machining of work pieces to a predetermined size. Another object is to provide improved means for actuating and resetting the releasable sizing levers or electric contact making members of a sizing gauge. Another object is to provide improved means for actuating a feeler gauge, as to control its engagement with and separation from the work.

To these ends and also to improve generally upon devices of this character, the invention consists in the various matters hereinafter described and claimed. In its broader aspects, the invention is not necessarily limited to the specific construction selected for illustrative purposes in the accompanying drawings in which

Fig. 1 is a front elevation of the machine.

Fig. 2 is a sectional view of a detail.

Fig. 3 is a side view, partly in section, of the rockable gauge mounting and associated parts.

Fig. 4 is an end view of some of the elements of Fig. 3.

Fig. 5 is chiefly a front elevation of gauging instrumentalities, the gauge box cover being removed and some parts being broken away and in section.

Fig. 6 is a side view of the gauge box.

Fig. 7 is a vertical section of Fig. 6.

Fig. 8 is an electrical and hydraulic diagram and

Fig. 9 is a diagram of the fluid system.

This application is a division of my application, Serial Number 348,398 which is now Patent 2,311,213 and which shows co-operating mechanisms in more detail.

The work surface to be gauged during a machining operation such as grinding is herein shown for example as a tapered surface 2 (Fig. 4) on the inner race ring 6 for a tapered roller bearing which is clamped in a chuck C whose spindle is journalled in a work head H and driven by a pulley 42 connected by a belt (not shown) to a pulley 136 on a shaft 138 journalled in a housing 140 on a swivel plate 142. The swivel plate is adjustable around a vertical axis through which a drive shaft 154 extends. The work surface is contacted by a work sizing feeler or fork gauge G during grinding and the work piece is ejected after grinding by an ejector E carried on a pivoted lever which is actuated by a link 176. The work is loaded by a loader indicated generally at L and comprising a movable

carrier 522 receiving the work pieces in succession from a magazine 526, the carrier being mounted on a slide 510 which is reciprocated by a cylinder unit 544, all mounted on a bracket 504 whose base 502 is fastened to the housing 140.

When the work head H is adjusted to the proper angle, the raceway surface is ground by a grinding wheel W which is fed normal to the surface by a feed slide 600 guided by dovetail ways of a base plate 602, the wheel spindle preferably being given a short reciprocation by gearing in a casing 601. During grinding, the feed slide is fed by a feed screw which can be operated manually by a hand wheel 674 having a handle 676 or by pawl and ratchet mechanism which is actuated by cylinder and piston units. A pawl 706 on an arm 710 which is pivoted to a piston rod 712 projecting from a cylinder 722 has an adjustable throw which is first ample for coarse feed and thereafter more limited for fine feed. A bar 716 clamped on the piston rod carries two adjustable limit screws 724 and 726, the first adapted to engage a stop lug 727 on the cylinder during coarse feeding. The other screw 726 restricts the stroke of the piston rod for fine feeding when a swinging latch lever 728 is swung under it. The latch lever is a bell crank pivoted on the cylinder and urged to inoperative outward position by a coil spring 730. The lever is moved to operative position by a push solenoid 734 which is actuated under control of the work gauge which completes the solenoid circuit when the work is nearly down to size, as will later appear. The ratchet mechanism is later turned backwardly or reset by a pawl 686 on an arm 690 actuated by a retracting cylinder unit 760. The pawl 686 normally engages a stop screw 752 adjustably mounted in a fixed lug 754.

The work contacting feeler or forked gauge G is mounted for pivotal movement (Figs. 3 and 4) on a bracket 164 attached to the work head, the pivotal axis and a portion of the bracket being inclined. The bracket has secured to its lower portion a block with a projecting bearing sleeve 402 in line with an upper bearing sleeve on a similar block 404 at the upper portion of the bracket. Each sleeve has a bushing to receive, respectively, a lower pivot stud 408 and an upper pivot stud 410 projecting from an inclined gauge bar 406 which has a recess in which the lower end of the feeler is fastened. The lower pivot stud 408 has a conical seat for a ball 412 which also bears in a conical seat in a slideable sleeve 414 which is urged upwardly by a coiled centering spring which is seated on a plate 418 made

adjustable by a screw 420 threaded in a bearing cap 422. The centering spring lets the gauge feeler float and center itself by contact with the work, the pivot studs being slidable axially in their bushings to a small extent.

The upper stud 410 is long enough to project through the upper bearing sleeve and has an arm 424 pinned thereto, the arm carrying a water seal 426 covering the upper bearing sleeve. The arm 424 projects upwardly and carries an adjusting screw 428 adapted to engage a hardened insert 430 in a shiftable actuating rod 432 which slides in guide bushings 434. On the top of the work head is a dovetail base plate 346 (Fig. 2) supporting a slide 348 having a standard 349 to which a bracket 356 is adjustably attached by bolts 360 passing through a slot 358. The bracket supports dressing mechanism (not shown and of no immediate interest) but its supporting base plate 346 is bored to receive and hold the above mentioned guide bushings 434. The rod 432 is urged in one direction by a coiled spring 438 and its inner end carries a fork 440 loosely embracing a head 442 on a plunger projecting from a gauge support or indicator box 444 adjustably mounted by a bracket 446 on the work head. As will later appear, the spring yieldably causes resetting of certain movable gauge contacts in the indicator box when the work sizing feeler or fork gauge G is moved out of engagement with the work, the spring then causing the fork 440 to pull the headed plunger outwardly to the right in Fig. 5. Hardened inserts are inserted between the head 442 and the fork 440 to transmit movement in the opposite direction from the rod 432 to the headed plunger during gauging.

The feeler G straddles the work and its two diamond feeler points are normally urged substantially parallel to the work axis and substantially lengthwise of the tapered work surface 2 being ground in order to promote sensitivity. The feeler is urged against the work by a coiled spring 448 interposed between a nut 450 and a slideable flanged bushing 452 which bears against a bifurcated actuating arm 454 attached to the pivoted gauge bar 406. The nut and the bushing are supported on a threaded stud 456 threaded in the end of a piston rod 458 and forming an extension thereof. The stud has an abutment or head 460 normally spaced from but adapted to engage the outer surface of the bifurcated arm 454 when the piston rod is pulled into its cylinder 462. This movement retracts the feeler from the work and controls the resetting of the gauge parts in the indicator box. When new work is inserted in the chuck, a needle valve indicated in the diagram causes the piston rod 458 to delay the return of the feeler until the surface has been ground well down towards the desired size.

The headed plunger 442 slides in a boss 464 on the indicator box and the end of it engages the actuating arm of a bell crank lever 466 pivoted on a pivot screw 468 and carrying a plate in the form of a cylinder 470 which engages the stem 472 of a visual indicator 474. The bell crank lever is urged in one direction by a coil spring 476 to cause its actuating arm to engage the inner end of the headed plunger 442. A pair of releasable contact making or sizing levers 478 are pivoted on an eccentric shaft 480 which is angularly adjusted by a knob 482 and clamped by a nut 484. Each lever carries a contact screw 486 adapted to engage a contact screw 488 on the box to complete an electric circuit. A coil spring 490 urges each lever in a direction to engage its hardened

insert 492 with the cylinder or arresting plate 470 and eventually to snap the lever to circuit completing position under control of the cylinder or arresting plate 470 which moves very slowly upwardly as the work changes in size. One lever is arranged to snap past the cylinder before the other, the two levers each having a slit and a wedging screw 494 so that one can be adjusted to be slightly shorter than the other. As will appear, the first circuit to be completed energizes a solenoid which reduces the feed of a grinding wheel ratchet mechanism from coarse to fine and the other energizes a solenoid to stop a pawl feeding motor. When the work feeler or gauge G is withdrawn from the work, the sizing levers 478 are reset by the headed plunger 442 which is pivoted loosely by a pin to a resetting lever 496 having hooks 498 to engage behind bent pins 500 on the sizing levers.

Referring to Figs. 8 and 9 showing the electrical and hydraulic circuits and assuming a work piece has been carried to the chuck by the loader, the cylinder unit 544 causes retreat of the loader and starts the grinding cycle by closing a normally open switch 552. This energizes a coil 798 thereby closing a two-pole switch 800 which causes a coil 802 to reverse a main reversing valve 804 supplied with pressure fluid from a pump 806. Pressure fluid is directed through a pipe 808 to a series of cylinders. Cylinder 626 causes the grinding wheel to have a preliminary quick advance ready for the ratchet operated coarse feed. Cylinder 760 moves the retracting ratchet pawl in the idle direction ready to cause feed retraction when grinding is done. The gauge shifting cylinder 462 shifts the feeler towards the work but this movement is rendered slow by a needle or throttle valve 810 and a ball check valve 812 which communicate with the pressure line or pipe 808 so that contact of the feeler with the work is postponed until the work has received considerable grinding, thus lessening wear. The ball check valve by-passes the fluid only when the fluid afterwards exhausts to the pipe 808.

As the main wheel slide is thus rapidly shifted forwardly by the cylinder 626, a contact screw 650 closes a normally open switch 652 thereby energizing a coil 814 which closes a normally open three-pole switch 816 and starts a pawl actuating motor 818 having a cam 820 which repeatedly reciprocates the plunger of a valve 822 piped to a pilot valve 824 which causes repeated reciprocation of the piston rod in the pawl feeding cylinder 722. Thus the feed pawl first imparts coarse feeding strokes as determined by the stop screw 724 of Fig. 1. As grinding proceeds, the feeler gauge controls the release of the first sizing lever in the indicator box and a circuit is completed by the corresponding contact screws 486 and 488 to thereby close a normally open switch 826. This causes the solenoid 734 to be energized to swing the latch lever 728 and reduce the stroke of the pawl.

As the work reaches final size, the feeler gauge controls the completion of the second gauge circuit and actuates a double acting switch 828 one portion of which opens the circuit of the switch 816 to stop the feed motor 818. The switch 828 also closes a circuit which starts a timing switch 830 which keeps the wheel advanced to spark out for a short interval. When the timing switch contacts close at 832 and open at 834, coils 836 and 838 are thus energized, the latter closing a normally open switch 840 to energize a coil 842 and reverse the main valve 804. Thus the pipe

line 860 becomes an exhaust line so that cylinder unit 626 retracts the main wheel slide while cylinder unit 462 quickly retracts the feeler gauge and resets the movable gauge contacts and the retracting cylinder 760 resets the ratchet mechanism ready for a new feed. At about the same time coil 836 reverses a four-way valve 844 and the chucking cylinder 680 operates to release the work.

As the cylinder unit 626 thus retracts the wheel, a switch 664 is closed and energizes a solenoid 184 to operate the ejector. A solenoid 846 is also energized to reverse a four-way valve 848 which causes the loading cylinder 544 to advance the loader with a new work piece and, as that cylinder completes its action, a switch 548 is closed to energize a solenoid 850 and thereby reverse the valve 844 so that the chucking cylinder causes the new piece to be clamped, the operation of the chucking cylinder then closing the switch 110 to energize a solenoid 852 and reverse the valve 848 to retract the loader which starts the new grinding cycle.

There is another grinding wheel (not shown) on the machine to grind a conical shoulder on the work, the wheel being advanced by a feed cylinder 260 and being afterwards dressed under control of a cylinder 364 and a valve 858. This dressing can be made to occur at every cycle by keeping closed a switch 854. Then as the cylinder 260 which is connected to the main valve 804 causes a switch 262 to close, a coil 220 effects compensation for wheel wear and dressing while a solenoid 856 reverses a valve 858 to operate the dressing cylinder 364. The latter first closes a switch 377 to energize a coil 860 for cooling water and later closes a switch 377A to energize a coil 862 to thereby make the valve 858 return the dresser.

I claim:

1. In a machine of the character indicated, a work head, a grinding wheel, the work head and the grinding wheel being mounted for relative movement of approach, a work engaging feeler, a spring urging the feeler towards the work, a piston and cylinder unit for rapidly moving the feeler to retract the feeler from the work, a throttle valve for slowing the movement of the piston in the other direction to postpone the contact of the feeler with the work, and means for bringing the work and the grinding wheel into contact prior to contact of the feeler with the work.

2. In a machine of the character indicated, a work engaging feeler, an actuating arm for moving the feeler, a spring for urging the feeler towards the work, a piston rod having an abutment normally spaced from the arm, the piston rod supporting the spring at one side of the arm and supporting the abutment on the other side, a cylinder for moving the piston rod to carry the abutment against the arm to render the spring ineffective and retract the feeler from the work, a sizing member, and means for transmitting movement of the feeler to the sizing member to determine the size of the work.

3. In a machine of the character indicated, a work engaging feeler, an actuating arm for moving the feeler, a spring for urging the feeler towards the work, a piston rod passing through the spring and extending from one side of the arm to the other, the piston rod having a head normally spaced from the arm on the side opposite to the spring, a cylinder for moving the piston rod to bring the head into or out of contact with the arm, a sizing member, and means for

transmitting movement from the feeler to the sizing member.

4. In a machine of the character indicated, a work head, a tool head, a power unit connected to a source of fluid pressure for bringing the tool and the work into machining contact, a work engaging feeler, an actuating arm for moving the feeler, a spring for urging the feeler towards the work, a piston rod for operating the arm, a cylinder having piping connections to the same source of fluid pressure as that of the power unit, and throttling means in one of the connections to the cylinder to prevent contact of the feeler with the work until the power unit has first operated and substantial machining has occurred.

5. In a machine of the character indicated, a work head for supporting a work piece, a tool head having a machining tool to engage the work piece, a work contacting feeler to control the size of the work, means for bringing the work and the tool into machining contact, and mechanism for moving the feeler towards the work, a controlling device for starting said means and said mechanism, and a retarding device in said mechanism for delaying contact of the feeler with the work until the work and the tool have been in machining contact for a substantial portion of the machining period.

6. In a machine of the character indicated, a work head for supporting a work piece, a tool head having a machining tool to engage the work piece, means for bringing the tool and the work into machining contact, a work contacting feeler to control the size of the work, a piston rod having piping connection with the feeler, a cylinder having piping connections for fluid pressure, a piston in the cylinder and connected to the piston rod, throttling means in one of the piping connections to postpone contact of the feeler with the work until the tool and the work have first been brought into contact and substantial machining has occurred, and means controlled by said feeler when the work reaches size for causing the cylinder to retract the feeler from the work.

7. In a machine of the character indicated, a gauge support, a movable contact making member movably mounted on the support, a plate for arresting and releasing the member, a lever movably supporting the plate and having an actuating arm, a plunger slideable in the gauge support and engaging the arm, a work engaging feeler, and means for transmitting gauging movement from the feeler to the plunger.

8. In a machine of the character indicated, a gauge support, a movable contact making member movably mounted on the support, a plate for arresting and releasing the member, a plunger slideable in the gauge support for actuating the plate to release the contact making member, a coil spring for moving the plunger in one direction, and a work engaging feeler for controlling movement of the plunger in the other direction.

9. In a machine of the character indicated, a gauge support, a movable contact making member movably mounted on the support, a plate for arresting and releasing the member, a plunger slideable in the gauge support for actuating the plate to release the contact making member, a resetting member connected to the plunger and having means to move the contact making member to arrested position, a work engaging feeler, and means for transmitting gauging movement from the feeler to the plunger.

10. In a machine of the character indicated, a

gauge support, a movable contact making member movably mounted on the support, a plate for arresting and releasing the member, a plunger slideable in the gauge support for actuating the plate to release the contact making member, a resetting member operated by the plunger and having means to restore the contact making member to arrested position, a coil spring for urging the plunger in the resetting direction, and a work engaging feeler controlling movement of the plunger in the other direction. 10

11. In a machine of the character indicated, a gauge support, a movable contact making member movably mounted on the support, a plate for arresting and releasing the member, a plunger slideable in the gauge support for actuating the plate to release the contact making member, a work engaging feeler, and a member for controlling transmission of movement from the feeler to the plunger, said last mentioned parts having a connection comprising a head on the one and an embracing fork on the other. 15

12. In a machine of the character indicated, a gauge support, a movable contact making member movably mounted on the support, a plate for arresting and releasing the member, a plunger slideable in the gauge support for actuating the plate to release the contact making member, a shiftable member for operating the plunger, a work engaging feeler for transmitting gauging movement to the plunger, the plunger and the shiftable member having a connection comprising a head on the one and a fork on the other. 20

13. In a machine of the character indicated, a gauge support, a movable contact making mem- 25

ber movably mounted on the support, a plate for arresting and releasing the member, a plunger slideable in the gauge support for actuating the plate to release the contact making member, and a resetting member connected to the plunger and having means to restore the contact making member to arrested position. 5

14. In a machine of the character indicated, a gauge support, a movable contact making member movably mounted on the support, a plate for arresting and releasing the member, a lever movably supporting the plate and having an actuating arm, a plunger engaging the arm, a sliding rod connected to the plunger, a work engaging feeler for sliding the rod in one direction, and a resetting lever connected to the plunger and having means to move the contact making member to arrested position. 10

15. In a machine of the character indicated, a work head, a gauge bar having a pivotal mounting, a feeler gauge secured to the bar and adapted to engage the work, an actuating arm secured to the gauge bar, the pivotal mounting comprising axially movable pivot studs on the gauge bar and a centering spring urging the studs axially. 15

16. In a machine of the character indicated, a work head, a gauge bar, a feeler gauge secured to the bar and adapted to engage the work, an actuating arm secured to the bar, pivot studs projecting from the gauge bar, bearings slidably and rotatably receiving the studs, one of the studs having a supporting ball at its end, and a spring exerting pressure on the ball. 20
